UNITED STATES PATENT OFFICE.

MAX SCHEUER, OF NEW YORK, N. Y.

BUCKLE.

SPECIFICATION forming part of Letters Patent No. 469,982, dated March 1, 1892.

Application filed November 12, 1891. Serial No. 411,670. (No model.)

To all whom it may concern:

Be it known that I, MAX SCHEUER, of New York, county and State of New York, have invented an Improved Buckle, of which 5 the following is a specification.

This invention relates to a buckle so constructed that it will expand under tension. Thus when it is attached to a belt or similar article the latter will closely fit the waist without oppressing the wearer.

The invention consists in the various features of improvement more fully pointed out in the claim.

In the accompanying drawings, Figure 1 is 15 an inner face view of the buckle; Fig. 2, an inner face view of the buckle-frame with the strip a^3 straight; Fig. 3, a corresponding view of the eye b . Fig. 4 is a longitudinal section through one end of the buckle-frame; Fig. 5, 20 a cross-section of the buckle on line xx , Fig. 4.

The letter a represents the plate or frame of a buckle having upset edges a' , to which the dog or hook a^2 is pivoted, as usual. To the one end of the frame a there are secured the 25 ends of two (more or less) springs c , preferably formed of coiled wire. To the opposite ends of these springs there is attached a slotted plate or eye b for the attachment of one end of any suitable belt. Thus it will be seen 30 that the buckle is provided with an elastic section between its attaching-eye and its frame, which permits the buckle to expand under tension.

The springs c are attached to the frame a 35 in the following manner: The frame a terminates in a strip a^3 , projecting laterally beyond the edges of the buckle, Fig. 2. This strip is provided with a series of corrugations

a^4 , as shown. These corrugations are bent forward so as to project at right angles to the 40 body of the strip. Next the springs c are placed with their ends upon the strip and then the latter is bent upon itself upon the dotted lines, Fig. 2. Thus it will be seen that the springs will be engaged by the corrugations a^4 , Fig. 4, which enter between two of the coils of each spring, and in this way all the springs are securely locked to the frame a . 45

The eye b is provided with a corrugated strip b' , Fig. 3, corresponding in all respects 50 to the strip a^3 , and which attaches the outer ends of the springs to the eye.

d is the eye that is engaged by the hook a^2 . To this eye are attached the springs c' , connected at their other ends to an eye e , to which 55 in turn the belt is attached. The eyes d and e are secured to their springs c' in the same manner as the springs c are secured to the frame a and eye b .

It will be seen that by employing two corresponding elastic sections to the right and left of the buckle-frame the latter is made to form the center of one symmetrical elastic buckle.

What I claim is—

The combination of plate a , having upset edges a' , with hook a^2 , pivoted thereto, springs c , secured to the plate, an eye b , connected to the outer ends of the springs, and with a pair of eyes d and connecting-springs c' , the eye d being adapted to engage hook a^2 , substantially as specified.

MAX SCHEUER.
